Primary Examiner—Wallace R. Burke**Assistant Examiner—H. Baynham****Attorney, Agent, or Firm—Lothrop & West****[57]****CLAIM**

The ornamental design for a sod shifter, as shown and described.

DESCRIPTION

FIG. 1 is a front perspective view of a sod shifter, showing my new design;

FIG. 2 is a front elevational view thereof;

FIG. 3 is a rear elevational view thereof;

FIG. 4 is an elevational view of one side thereof;

FIG. 5 is an elevational view of the other side thereof;

FIG. 6 is a top plan view thereof;

FIG. 7 is a bottom plan view thereof;

FIG. 8 is a perspective view of a second embodiment of the design shown in FIG. 1 wherein the only difference resides in the alternate position of the foot plate; and,

FIG. 9 is a perspective view of a third embodiment of the design shown in FIG. 1 wherein the only difference resides in the alternate position of the foot plate.

FIG. 1.

FIG. 2.

FIG. 3

FIG. 4.

FIG. 5.

FIG. 6.

FIG. 7.

FIG. 8.

FIG. 9.
